UNITED STATES PATENT OFFICE.

WILLIAM N. GRISWOLD, OF NEW YORK, N. Y.

REEFING SAILS.

SPECIFICATION forming part of Letters Patent No. 253,371, dated February 7, 1882.

Application filed December 5, 1881. (No model.)

To all whom it may concern:

Be it known that I, WILLIAM N. GRISWOLD, of New York city, county of New York, and State of New York, have invented certain new and useful Improvements in Reef-Booms, of which the following is a full, clear, and exact description, reference being had to the accompanying drawing, and to the letters of reference marked thereon.

10 My invention has relation to means for facilitating and assisting in shortening and carrying sail on fore-and-afters and other craft; and the objects of my invention are to render the sail capable of being handled by a smaller number of men than is required for handling ordinary forms of sails; to enable it to be reefed quickly, easily, and without danger or trouble, and to maintain the sail in better position when spread.

20 To accomplish these objects my invention consists essentially in the application to the sail of what I denominate my "reef-boom," and the proper or necessary adjuncts for moving the same, all of which will be herein first 25 fully described, and then pointed out in the claim.

In the accompanying drawing, forming part of this specification, I have shown a fore-and-aft sail with my improvements applied thereto. This illustration, in connection with the 30 following explanations, will be found sufficient to enable others skilled in the art to practice my invention.

35 A is the mast; B, the top-mast; C, the main-boom, and D the gaff. These are of the ordinary form and construction. S is the sail.

At the close-reef band or other part of the sail above the foot I apply the reef-boom E, the same being secured to or connected with 40 the sail, for which purpose the sail may be separated and fitted to be stoppered to the reef-boom; or a pocket may be formed in the sail at the desired location, and made to receive the reef-boom, substantially as indicated 45 in the drawing. Other means of connecting the reef-boom and sail may be adopted. The reef-boom E should be made of the best material for the purpose and of no greater weight and strength than are needed to take the bulge 50 strain of the sail when full of wind. Under ordinary circumstances a diameter of about one-third that of the main-boom will be found sufficient for all required purposes.

The reefing of a fore-and-aft sail, especially 55 in rough weather, is a difficult piece of work,

usually requiring "all hands," not infrequently accompanied by danger or accident, and consuming much valuable time. With my improved reef-boom the "watch on deck" can close-reef the sail very easily and quickly. 60 All that is necessary is to "luff" and shake the sail, lower a little on the throat-halyards F and peak-halyards G, and then set the reef-boom well down on the main-boom with the reef-gigs H H properly applied upon the two 65 booms, pass the necessary number of lashings around the two booms, sway upon the throat and peak halyards, and reset the sail. The reef-gigs H H may be conveniently united after passing the last block on the main-boom, 70 so as to form a single line, H', as indicated, and for the purpose of facilitating manipulation, as will be readily understood. The reef-boom being rigid, and being connected with the sail, obviates bulging to a great and beneficial extent, holding the sail flat, allowing the vessel to lie closer to the wind, and also enabling the vessel to carry sail in threatening weather for a greater length of time with perfect safety. 75

The improvement is applicable to old sail as well as new. No alterations are required, only the additions necessary to work the reef-boom.

When constructed and arranged to operate in accordance with the foregoing explanations 80 the improved arrangement will be found to admirably answer the several purposes and objects of the invention, as previously stated, and not to interfere in any manner with the proper working of the sail. 85

More than one reef-boom may be applied to the sail, if desired.

Having now fully described my invention, what I claim as new, and desire to secure by Letters Patent, is—

In a fore-and-aft sail, the rising and falling reef-boom located in a pocket in said sail between the gaff and main-boom, and combined with suitable lines for hauling it down upon the main-boom and setting it in position thereon for the purpose of reefing the sail, substantially as shown and described. 90

In testimony that I claim the foregoing I have hereunto set my hand in the presence of two witnesses.

W. N. GRISWOLD.

Witnesses:

F. W. HANAFORD,
WORTH OSGOOD.
